Patented Aug. 19, 1975

236,336

BICYCLE FORK

Thomas D. Seifert, Aracadia, Calif., assignor to
LRV Industries, South El Monte, Calif.

Filed Nov. 4, 1974, Ser. No. 520,632

Term of patent 14 years

Int. Cl. D12—II

U.S. Cl. D12—118

Fig. 1.

Fig. 3.

Fig. 4.

Fig. 5.

FIG. 1 is a side elevational view of a bicycle fork showing my new design;

FIG. 2 is a front perspective view thereof;

FIG. 3 is a rear perspective view thereof;

FIG. 4 is a top plan view thereof; and

FIG. 5 is a bottom plan view thereof.

The broken line showing of a bicycle to which the fork is attached is for purposes of illustration only.

I claim:

The ornamental design for a bicycle fork, as shown and described.
